ELECTRICAL METHOD FOR MANUFACTUR-
ING SULPHONATED OILSWilliam Woelflin, Long Beach, Calif., assignor to
Petroleum Rectifying Company of California,
Los Angeles, Calif., a corporation of CaliforniaApplication December 26, 1933, Serial No. 703,945
Renewed June 5, 1937

19 Claims. (Cl. 204—9)

My invention relates to an improved electrical process and apparatus for the manufacture of sulphonated oils such as textile oils, leather oils, chemical emulsifying and demulsifying agents 5 and the like, such as are used in the textile, leather or other industries.

In general the problem of manufacturing sulphonated oils and sulphonated fatty materials is not new. Oils, fats, and the fatty acids occurring 10 therein have previously been reacted with sulphuric acid, oleum, chlorosulphonic acid, etc., and the resulting products of such reactions have found utility in the textile, leather, and other industries, especially in a partially or completely 15 neutralized state, these products being sulphon-fatty bodies and containing in some cases acid sulphates, and in others true sulphonic acids. More recently the higher alcohols, e. g., cetyl alcohol, have been employed as ingredients in similar 20 processes to produce sulpho-bodies of somewhat similar properties.

The present process relates to an improved process and apparatus for the manufacture of such sulphon-fatty materials and particularly to 25 a sulphonation process using sulphuric acid as a reaction agent. I shall hereinafter employ the term "organic fatty body capable of reaction with sulphuric acid or a derivative thereof" for the material preliminarily treated in the manufacture 30 of such products. By the word "derivative" in this term, I have reference to a derivative which is an equivalent of the sulphuric acid. In this term are included fatty bodies such as glycerides, animal and vegetable oils, fats, waxes and 35 the fatty acids occurring therein, as well as the higher aliphatic alcohols, which latter resemble the oils, fats, and waxes in physical appearance and in many of their properties. Of these higher alcohols, I include specifically those having more 40 than eight carbon atoms in the molecule, of which group cetyl alcohol, octadecyl alcohol, methylsulphide alcohol, and ceryl alcohol may be named as examples.

The fatty bodies referred to above includes the 45 unsaturated oils, fats, and fatty acids commonly employed in preparing sulphonated fatty derivatives. They also include other fatty materials, e. g., hydroxystearic acid, which owe their reactivity, in the presence of sulphuric acid or its 50 derivatives, to the existence of a reactive group, like the hydroxyl group, in the molecule. The more common members of this group of organic fatty bodies capable of reaction with sulphuric acid are olive oil, castor oil, fish oils, sperm oil, whale oil, oleic acid (red oil), etc. In some cases,

the fatty raw material employed in making sulphon-fatty bodies is a mixture of fatty acids and glycerides prepared by splitting or partially splitting triglycerides by means of acids or splitting agents like Twitchell reagents.

5

The presently described process is also applicable to the preparation of such materials as Twitchell reagents, which are the products of sulphonation of a fatty body and an aromatic body by means of sulphuric acid or a derivative 10 thereof, this material to be sulphonated being included within the term "organic fatty body capable of reaction with sulphuric acid or a derivative thereof".

The present process is then, in general, applicable 15 to sulphonation reactions in which the principal ingredient is an organic fatty body capable of reaction with sulphuric acid or a derivative thereof, as herein defined. There may be present, in addition to these primary ingredients, 20 various other reactive or inert ingredients, such as petroleum distillates, aromatic bodies, like benzol or naphthalene or phenol, carbon tetrachloride, etc.

The process of this invention is applicable in 25 the preparation of sulphonated fatty derivatives containing large percentages of sulphon-compounds, as well as in the preparation of sulphonated fatty bodies in which the percentage of sulphon-compounds is small, i. e., in which the 30 amount of organically combined sulphur trioxide present is very small.

The products of such sulphonation processes I shall refer to as sulphon-fatty bodies, or sulphon-fatty derivatives, it being distinctly understood 35 that in these terms I include not only sulphonated oils and sulphonated fatty acids, but also sulphon-alcohols and sulphon-aromatic fatty bodies. The sulphon-bodies referred to herein may be either true sulphonic bodies, containing the sulphon group, or they may be acid sulphate bodies containing the sulphate group.

The present method of manufacturing such sulphon-fatty materials consists usually of the following general steps: (1) Mixing a sulphonating agent in the form of sulphuric acid or a suitable derivative thereof with an organic fatty body capable of reaction with such sulphur acid, either alone or with the addition of suitable solvents, diluents, or other ingredients, allowing the reaction 45 to proceed for a desired length of time and at a desired temperature. (2) Washing the acidic reaction mass with a suitable amount of an aqueous washing medium which may be water or other suitable aqueous solution. By wash- 50

55

ing, I mean mixing or contacting, more or less intimately, the acidic reaction mass and the suitable aqueous medium. In most cases, mixing is continued until a homogeneous mixture is produced, which may separate more or less slowly. (3) Allowing the mixture to stand in a quiescent state until it separates into two layers. The excess sulphonating agent and the washing medium, with possibly some water-soluble organic matter, like glycerin, comprise the lower aqueous layer, leaving an oily supernatant layer in the upper part of the settling zone. (4) Withdrawing the lower aqueous layer. (5) Partially or completely neutralizing the oily supernatant layer consisting of sulphonated, sulphated, or otherwise altered fatty material, this neutralizing action being effected by adding a suitable neutralizing agent, usually one of the common alkali metal bases, caustic soda, caustic potash, anhydrous or aqueous ammonia, etc., or one of the alkali carbonates or bicarbonates, or other bases like those of the alkaline earth metals. (6) Allowing the neutralized or partially neutralized mass to stand in a quiescent state to permit settling therein of the small amount of aqueous solution remaining after the first settling period and the neutralizing step, as well as to allow a settling of more or less of the water which may have been added with the neutralizing agent.

The length of time required for these separatory steps is quite large. The first such step, wherein the lower aqueous layer is formed after washing the acidic reaction mass, frequently requires from eight to thirty-six hours, depending on the temperatures employed in washing, the nature of the ingredients, the reaction temperature employed, and other factors. The second separatory step also requires a prolonged time of settling to remove the water or aqueous solution. In some cases separation of aqueous material continues for as long as a month, and products behaving in this fashion cannot be safely marketed until substantially all traces of this material are removed. Centrifugal methods are commonly ineffectual in that they fail materially to accelerate and facilitate the separation and stratification of the constituents.

Not only do either or both of these settling steps result in a great waste of time and necessitate much additional equipment which would otherwise be unnecessary, but my experiments have shown that it is very undesirable to maintain such water or aqueous solutions in contact with the sulphonated products. I have found that prolonged contact between these materials produces undesirable side reactions which materially decrease the effectiveness of the finished product. Among these side reactions may be cited hydrolytic and polymerizing reactions which are quite detrimental to the finished product.

Furthermore, incomplete and imperfect separation of the aqueous material before neutralization results in the retention of excessive amounts of the sulphonating agent by the oily acidic mass after washing and settling. This causes the amount of neutralizing agent required to be excessive, which in turn results in higher costs and, if the neutralizing base be employed in aqueous solution, also results in undesirable dilution of the product. Other disadvantages are, for example, the inclusion of large amounts of mineral sulphates which may separate on standing, or which may cloud or otherwise dis-

color the product or be detrimental to the appearance or quality thereof.

In the present process the above-mentioned defects are overcome and a superior product is obtained by utilizing electrical means for assisting in performing either or both separating steps. Thus, the acidic reaction mass, together with the water or other aqueous medium mixed therewith, may be subjected to the action of an electric field which quickly coalesces the excess of water or aqueous medium and sulphonating agent into masses of sufficient size to be easily and rapidly removed by gravitational or centrifugal methods. The same method can be used in separating the neutralized or partly neutralized material.

Among the important objects of the present invention is the provision of a method and apparatus for forming such sulphonated products which effects not only a distinct saving of time, apparatus and materials in the manufacture of these products, but which has been found to produce an improved and superior product of increased effectiveness.

It is a further object of the invention to provide a novel step in the process of producing sulphonated fatty derivatives, wherein a mixture of an acidic reaction mass and a washing medium is subjected to the action of an electric field.

A further object lies in the subjection of a finished or a semi-finished product consisting of a partially or completely neutralized sulphonated fatty derivative to the action of an electric field.

A further advantage of the present process is that a saving is effected in the amount of neutralizing agent needed to neutralize the material to a desired point, as compared with the amount needed when prolonged gravitational settling is resorted to, and it is a further object of the invention to provide a process and apparatus which accomplishes such a saving in the amount of materials required.

It is not necessary to the present process that an anhydrous product be obtained. The sulphonated fatty derivatives prepared in accordance with the present process may sometimes still contain considerable amounts of water, though in many instances the process results in the production of a product containing only traces of water.

It has sometimes been found desirable to utilize an electric field of special oscillatory character, and it is another object of the present invention to use one or more electric fields of this character in the removal of excess water or other aqueous constituents from a sulphonated fatty derivative.

Other objects and advantages of the invention will be made apparent hereinafter.

The said organic fatty body capable of reaction with sulphuric acid or a derivative thereof is first mixed with the sulphuric acid or other suitable sulphonating agent in a reaction or mixing chamber of any common or desired form, with or without the addition of diluents, solvents, reactive or inert aromatics, etc. In the annexed drawing, I have diagrammatically shown a tank 10 into which these organic fatty materials, etc., and the sulphonating agent are respectively introduced through pipes 11 and 12. These materials may be stirred by any suitable agitator means, not shown, or by a wooden paddle. The result is the formation of an acidic reaction mass.

When the reaction has proceeded for the de-

sired length of time, the acidic reaction mass may be transferred to a washing chamber or it may be washed in the same tank 10 without transference to a second vessel. Thus, in the latter process, the aqueous washing medium in the form of water or other suitable aqueous medium commonly employed to remove the excess sulphonating agent from such mass, such as sodium chloride, or sodium sulphate solution, is introduced into the tank 10 by any suitable means. Diagrammatically, I have illustrated a pipe 13 for introducing this aqueous washing medium into the lower end of the tank 10. This washing medium is intimately admixed with the acidic reaction mass by any suitable agitator positioned in the tank 10 or by manual means.

If desired, the mixture may be allowed preliminarily to settle in the tank 10 to permit the bulk of the aqueous medium, consisting of washing medium, excess sulphonating agent, and any other ingredients of the acidic reaction mass such as glycerol, which may be preferentially soluble in water, to separate naturally by gravity, reserving the application of the electrical treatment for the removal of the last traces of removable aqueous material. If this is done the material which gravitationally separates can be removed through a pipe 14, allowing the remainder of the material to move through a pipe 15 to the electric treater 20. Generally, however, the process of this invention is most advantageously employed by quickly subjecting the whole mixture of acidic reaction mass and washing medium to the action of an electric field to separate the removable aqueous material as rapidly and completely as possible, for reasons previously recited herein. In this instance the entire mass of material is moved through the pipe 15 and into the treater 20.

As diagrammatically illustrated, this treater 20 may include a tank 21 comprising an outer grounded electrode on which insulators 22 are supported. These insulators, of any desired number, carry a cross bar 23 which adjustably mounts a rod 24, which latter element may, in some instances, in itself comprise an inner electrode. In the exemplary form shown, a screen electrode 25 is retained at the lower end of the rod 24. As treatment progresses, there is formed in the bottom of the tank 21 an aqueous layer the level of which slowly rises until the mixture has been substantially completely separated. I have indicated the ultimate uppermost surface of this lower aqueous layer by the dotted line 27, and have found it preferable to position the screen electrode 25 a slight distance above this surface 27. If, then, a potential difference is maintained between the tank 21 and the rod 24, treatment will take place not only in the space around the rod, i. e., between this rod and the tank 21, but will also take place between the screen electrode 25 and the tank 21. In addition, treatment will take place between the screen electrode 25 and the surface of the aqueous lower layer which is of a conducting nature. The electrode 25 and the rod 24 should not at any time be submerged below the upper level of this lower aqueous layer, since short-circuiting would be caused.

It is to be distinctly understood that the position of the rod and electrode in relation to the surface of the lower aqueous layer is not to be regarded as necessarily fixed. Different reaction masses may require different adjustments of the rod and electrode to attain most efficient sepa-

ration of the aqueous layer. In some cases, the rod and electrode may be so mounted or moved that a constant distance is maintained between the electrode and the constantly rising surface of the said aqueous layer, i. e., the electrode may be constantly raised as separation proceeds under the influence of the process.

In other instances the electrode structure may be retained in a fixed position in the tank 21 so that as the level indicated by the dotted line 27 rises the field between this level and the screen electrode 25 will increase in intensity.

Any suitable means may be utilized for building a potential between the rod 24 and the tank 21. Best results are obtained if an alternating or pulsating current is utilized. In many instances it is possible to secure entirely satisfactory treatment by connecting the high tension winding of a transformer between the tank 21 and the rod 24, this transformer being one which builds a high voltage therebetween. Potentials less than 10,000 volts in magnitude are ordinarily very satisfactory, though usually the potentials employed should be above 1,000 volts. Very satisfactory results will thus accrue if a 5500-volt transformer is utilized thereby making an average gradient of 1,000 volts per inch. These limits are, however, not exclusive, for in some instances it is possible to use potentials higher or lower than those above mentioned. The limits set forth are illustrative, and I do not limit myself thereto. With such a system the alternating potential can be continuously applied or can be periodically interrupted to form a series of impulses. Such impulses may be of a duration of one-half cycle if desired, or may be of such length as to include more than one-half cycle or several complete cycles if desired.

In some instances it has been found desirable to utilize the circuit shown in the accompanying drawing, especially when treating masses of an especially conducting nature. In the form shown, I have illustrated a transformer 30 including a high voltage winding 31, one terminal of which is grounded and connected to the tank 21. The other terminal is connected to the rod 24 through a spark gap 33. It is usually preferable, though not always necessary, to place a condenser 34 across the high tension winding 31, as shown. The transformer 30 includes a low tension winding 35 which is connected to a suitable commercial-frequency supply line through a choke coil 36.

When a treater thus connected is placed in operation, the current flow through the treating space will be limited by the choke coil 36. At the same time, by proper adjustment of the spark gap 33, this gap will periodically break down as the potential thereacross builds up. Thus, as the potential across the electrodes is building up, the condenser 34 will be charged, and when a sufficiently high potential is attained, the spark gap 33 will break down. At this instant, a low resistance path is formed across the terminals of the spark gap and current can flow therethrough to the electrodes. During this breakdown period, the condenser 34 discharges to the electrodes. This discharge is an oscillatory one and is usually of high frequency, this frequency being determined by the electrical characteristics of the condenser 34 and the remainder of the circuit. However, any current flowing to the electrodes decreases the potential across the winding 31, especially when a choke coil 36 is being used. Thus, the potential is reduced to such

an extent that the arc will not persist across the spark gap 33, thus stopping a major portion of the current flow to the electrodes. The cycle is repeated when the potential across the transformer winding 31 again builds up. Other types of high frequency systems producing an oscillatory potential may also be used to advantage. Further, by using a rectifier with spark gap and condenser, direct-current impulses can be obtained. These may also be used to advantage in certain instances.

After such electrical treatment the lower aqueous layer may be withdrawn from the tank 21 through a pipe 40 including a valve 41. Thereafter the oily acidic mass remaining in the treater may be neutralized therein, or it may be removed from the treater to another container in which this neutralization takes place. In the form illustrated the electrode structure is so formed as to be easily removable from the insulators 22, thus permitting the neutralization step to take place in the tank 21. The neutralizing agent may be added by any suitable means, as by a pipe 42.

This neutralizing agent is in the form of a suitable base. The common neutralizing agents are sodium, potassium, and ammonium hydroxides, although any other base may be employed as desired. For example, alkaline earth metal bases may be used, or the carbonate or bicarbonate of any desired metal or metal equivalent may be used in this capacity. The neutralizing agent is suitably mixed with the reaction mass, as by being stirred or otherwise agitated either manually or mechanically by means not shown.

35 In some instances it is possible to neutralize to the desired degree in a single step. In this instance the inorganic and the organic acids present are neutralized to the desired point by the addition of the proper amount of neutralizing agent. In this instance the resulting product may be removed through the pipe 40 or it may be allowed to settle for a time in the tank 21. Usually, however, it is desirable again to subject the neutralized or partially neutralized mass to the action of an electric field as will be hereinafter described.

In other instances it is desirable to vary this procedure, and, instead of neutralizing the oily acidic mass to its final degree in one operation as is performed in the common process of manufacturing sulphonated oils, to conduct the neutralization in two or more steps. For example, it may be desirable to neutralize in the first step only the strong acidic hydrogen that is due to the sulphuric acid and the organic sulpho-bodies present in the mass. Such a procedure would thus permit the settling of mineral sulphates, water and other similar aqueous or water-soluble material before completing the neutralization in one or more subsequent steps. In this way the presence of excessive amounts of such inert and frequently undesirable substances can be avoided. The subsequent neutralizing step or steps would be used for the purpose of neutralizing the product to any desired degree, e. g., until a water-soluble oil is obtained. The product can be carried to the point of complete neutralization if desired, or neutralization may stop short thereof, depending upon the product to be produced. If such a poly-step neutralizing process is carried out, it has been found very desirable to subject the semi-finished product to the action of an electric field, thus greatly decreasing the time necessary to separate the removable material. An advantage accruing from subjecting such semi-neutral-

ized products to the electrical separation process of the invention is that a product of superior homogeneity can frequently be so prepared. For example, sulpho-fatty materials that have been neutralized only slightly past the point where all the strong acidic hydrogen has been neutralized are sometimes marketed in this form and find particular utility in certain commercial processes over products which are neutralized to a greater degree. If the separation is allowed to take place by gravitational means, such relatively unneutralized products exhibit the very undesirable property of settling water or other aqueous solution over an extended period of time. If, therefore, such products are marketed immediately upon completion of manufacture, the separation of such aqueous material in the container produces an unfavorable reaction on the purchaser.

Thus, regardless of whether partial or complete neutralization is effected, it is usually desirable to subject the neutralized or partially neutralized mass to the action of an electric field. This can be accomplished by reinserting the electrode structure in the tank 21 and establishing the fields therein so as to coalesce and quickly remove the water or other aqueous solution. A superior product is produced if such foreign substances are removed in a short period of time, as hereinbefore mentioned. The electric field utilized in conjunction with the neutralizing step may be of an alternating or pulsating type, as previously described. With certain materials it is desirable to use the oscillatory system illustrated, though it will be understood that the utility of the process is not dependent upon the use of such a field of high frequency oscillating potential.

If a poly-step neutralizing process is utilized this electric treating step can be performed either between the time that the respective neutralizing steps are taken or after the desired degree of neutralization has been obtained by this poly-step neutralizing process.

It should be understood that I am not limited to the particular apparatus shown. If desired the tank 10 can be dispensed with and the sulphonating agent and washing medium added directly to the tank 21 during the time that the electrode is not positioned therein. So also it is possible to perform the neutralizing step in a container separate from the tank 21. So also, if desired, the electrical treatment of the neutralized or partially neutralized product can be effected by the use of an entirely separate electric treater similar to that indicated by the numeral 20. Furthermore, while it is usually desirable to utilize the invention in conjunction with a batch process, it will be apparent that my process is equally applicable to the preparation of sulpho-fatty bodies by continuous processes and the use of the word "mass" in the appended claims is not to be construed as limiting same to a batch process.

I claim as my invention:

1. An improvement in the process of manufacturing sulpho-fatty bodies, which improvement includes the steps of: intimately contacting the reaction organic fatty body to be sulphonated and a sulphonating agent to form an acidic reaction mass; mixing said acidic reaction mass with an aqueous washing medium; separating at least a part of said aqueous washing medium by applying to the mixture an electric field; withdrawing the separated aqueous layer; at least partially neutralizing the remaining oily acidic mass; and subjecting said partially neutralized mass to the

action of an electric field to separate aqueous material therefrom.

2. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; and then subjecting the resulting mixture to the action of a high-intensity electric field to quickly separate the oily portion of the acidic reaction mass from the aqueous washing medium and substances associated therewith, thereby preventing prolonged contact which would set up deleterious side reactions.

3. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; subjecting the washed acidic reaction mass to the action of a high-intensity electric field to coalesce at least a part of the aqueous material; settling said coalesced material to form an aqueous layer; withdrawing the material in said aqueous layer; and separately withdrawing the remainder of the reaction mass.

4. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; immediately subjecting the mixture to the action of a high-intensity electric field to coalesce at least a part of the aqueous material; and relatively quickly separating said aqueous material thus coalesced from the remainder of the mass to prevent prolonged contact which would set up deleterious side reactions.

5. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; allowing the mixture to stand in a quiescent state until a portion of the washing medium and other material preferentially soluble in water have separated; and thereafter separating the only portion of said washing medium and the remainder of said reaction mass by subjecting to the action of a high-intensity electric field.

6. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; separating at least a portion of the aqueous washing medium to leave an oily acidic mass; at least partially neutralizing said oily acidic mass; and subjecting the resultant product to the action of an electric field of high intensity.

7. An improvement in the process of manufacturing sulpho-fatty bodies by adding a sulphonating agent to an organic fatty body capable of

reaction with sulphuric acid or a derivative thereof to form an acidic reaction mass, which improvement includes the steps of: mixing said acidic reaction mass with an aqueous washing medium; separating at least a portion of the aqueous washing medium to leave an oily acidic mass; partially but not completely neutralizing said oily acidic mass; subjecting the resultant product to the action of an electric field of high intensity to coalesce at least a part of the aqueous material removable therefrom; allowing the electrically treated material to settle to form an aqueous layer; and removing said aqueous layer.

8. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; separating at least a portion of the aqueous washing medium to leave an oily acidic mass; partially neutralizing said oily acidic mass; subjecting the resultant product to the action of an electric field of high intensity; and subsequently further neutralizing the material treated by said electric field.

9. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; separating at least a portion of the aqueous washing medium to leave an oily acidic mass; at least partially neutralizing said oily acidic mass; subjecting the resultant product to the action of an electric field of high intensity to coalesce at least a part of the aqueous material therein; removing said coalesced material; and further neutralizing the product remaining after removal of said coalesced material.

10. An improvement in the process of manufacturing sulpho-fatty bodies as described in claim 2, in which said high-intensity electric field is of high frequency character.

11. An improvement in the process of manufacturing sulpho-fatty bodies by adding a sulphonating agent to an organic fatty body capable of reaction with sulphuric acid or a derivative thereof to form an acidic reaction mass, which improvement includes the steps of: periodically discharging a condenser in circuit with a pair of electrodes bounding a treating space to establish an electric stress in said treating space; mixing said acidic reaction mass with an aqueous washing medium; and subjecting the mixture to the action of said electric stress.

12. An improvement in the process of manufacturing sulpho-fatty bodies by adding a sulphonating agent to an organic fatty body capable of reaction with sulphuric acid or a derivative thereof to form an acidic reaction mass, which improvement includes the steps of: establishing an oscillatory electric field; mixing said acidic reaction mass with an aqueous washing medium; and subjecting the mixture to the action of said oscillatory electric field.

13. An improvement in the process of manufacturing sulpho-fatty bodies as described in claim 2, in which said high-intensity electric field is established by impressing an alternating

potential of commercial frequency across a pair of electrodes.

14. An improvement in the process of manufacturing sulpho-fatty bodies as described in claim 2, in which said high-intensity electric field is established by impressing an alternating potential across a pair of electrodes, and including the step of periodically impressing an oscillatory potential of high frequency across said electrodes.

15. An improvement in the process of manufacturing sulpho-fatty bodies as described in claim 2, in which said high-intensity electric field is established by impressing a potential between a pair of electrodes, and periodically interrupting said potential.

16. An improvement in the process of manufacturing sulpho-fatty bodies as described in claim 2, in which said high-intensity electric field is established by impressing an alternating potential between a pair of electrodes, and periodically interrupting said potential.

17. An improvement in the process of manufacturing sulpho-fatty bodies by adding a sulphonating agent to an organic fatty body capable of reaction with sulphuric acid or a derivative thereof to form a reaction mass, which improvement includes the steps of: mixing said reaction mass with an aqueous washing medium; separating at least a portion of said aqueous washing medium; then partly neutralizing the

washed mass by adding a base in insufficient quantities to completely neutralize same; then separating at least a part of the aqueous material from the partly-neutralized mass; thereafter adding additional quantities of a base; and subjecting the product resulting from the second neutralizing step to the action of a high-intensity electric field.

18. A process as defined in claim 17 in which said separation step performed between said neutralization steps is performed by subjecting the mass to the action of an electric field after the first addition of said base and prior to the subsequent neutralization to separate a portion of the first-added base prior to the subsequent neutralization.

19. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; subjecting the washed acidic reaction mass to the action of an electric field to separate at least a part of the aqueous material; at least partially neutralizing the resulting oily reaction mass; and subjecting the resulting product to the action of an electric field of high intensity.

potential of commercial frequency across a pair of electrodes.

14. An improvement in the process of manufacturing sulpho-fatty bodies as described in claim 2, in which said high-intensity electric field is established by impressing an alternating potential across a pair of electrodes, and including the step of periodically impressing an oscillatory potential of high frequency across said electrodes.

15. An improvement in the process of manufacturing sulpho-fatty bodies as described in claim 2, in which said high-intensity electric field is established by impressing a potential between a pair of electrodes, and periodically interrupting said potential.

16. An improvement in the process of manufacturing sulpho-fatty bodies as described in claim 2, in which said high-intensity electric field is established by impressing an alternating potential between a pair of electrodes, and periodically interrupting said potential.

17. An improvement in the process of manufacturing sulpho-fatty bodies by adding a sulphonating agent to an organic fatty body capable of reaction with sulphuric acid or a derivative thereof to form a reaction mass, which improvement includes the steps of: mixing said reaction mass with an aqueous washing medium; separating at least a portion of said aqueous washing medium; then partly neutralizing the

washed mass by adding a base in insufficient quantities to completely neutralize same; then separating at least a part of the aqueous material from the partly-neutralized mass; thereafter adding additional quantities of a base; and subjecting the product resulting from the second neutralizing step to the action of a high-intensity electric field.

18. A process as defined in claim 17 in which said separation step performed between said neutralization steps is performed by subjecting the mass to the action of an electric field after the first addition of said base and prior to the subsequent neutralization to separate a portion of the first-added base prior to the subsequent neutralization.

19. An improvement in the process of manufacturing sulpho-fatty bodies by adding a sulphonating agent to an organic fatty body capable of reaction with sulphuric acid or a derivative thereof to form an acidic reaction mass, which improvement includes the steps of: mixing said acidic reaction mass with an aqueous washing medium; subjecting the washed acidic reaction mass to the action of an electric field to separate at least a part of the aqueous material; at least partially neutralizing the resulting oily reaction mass; and subjecting the resulting product to the action of an electric field of high intensity.

Henry Van Arsdale,
Acting Commissioner of Patents.

CERTIFICATE OF CORRECTION.

Patent No. 2,110,899.

March 15, 1938.

WILLIAM WOELFLIN.

It is hereby certified that error appears in the printed specification of the above numbered patent requiring correction as follows: Page 2, first column, line 16, for "matterial" read material; page 5, first column, line 56, claim 5, for "only" read oily; and that the said Letters Patent should be read with these corrections therein that the same may conform to the record of the case in the Patent Office.

Signed and sealed this 10th day of May, A. D. 1938.

(Seal)

Henry Van Arsdale,
Acting Commissioner of Patents.
